United States Patent Office.

JOHN KINGSBOROUGH, OF CLEVELAND, OHIO.

Letters Patent No. 64,229, dated April 30, 1867.

SHIP-CHIMNEY JACK.

The Schedule referred to in these Letters Patent and making part of the same.

TO ALL WHOM IT MAY CONCERN:

Be it known that I, JOHN KINGSBOROUGH, of Cleveland, in the county of Cuyahoga, and State of Ohio, have invented certain new and useful improvements in Ship-Chimney Jacks; and I do hereby declare that the following is a full and complete description of the same, reference being had to the accompanying drawings, making a part of this specification, in which—

Figure 1 is a perspective view of the chimney jack.

Figure 2 is a horizontal section of the same.

Figure 3 is a longitudinal section.

Like letters of reference refer to like parts in the different views.

A, fig. 1, represents the chimney jack, which is designed to be used on shipboard in order to prevent the smoke descending the chimney, as it is liable to do in the present mode of constructing them, from the different currents of air to which a ship is subject. B B are slides or doors, which may be opened or closed at pleasure. C C, fig. 2, are deflectors or valves, pivoted to the ears a, fig. 3, so as to command the opening made by the slide B. These deflectors are hung so as to turn with the current of air as it strikes them. D D are guards, for a purpose hereafter shown; they also form standards or braces for supporting the upper part or cap of the chimney jack, by connecting the upper piece b to the lower piece e, which is directly connected to the chimney. Should the wind blow in the direction of the arrow d, fig. 2, the slides toward that point should be closed and the one opposite opened; this prevents the wind entering the chimney directly, but in striking the sails it often glances downward and backward, forming an opposite current or eddy, which coming in contact with the chimney will enter through the open slide. This current entering the largest opening e, impinges against the guard D, which has a tendency to throw it back against the chimney's side, and is carried around the channel or chamber I, by the force of the current entering the opening, and forced through the smaller opening f; this also aids in carrying the smoke through. When the current of air is in the direction of the arrow g, it strikes the deflector and turns it in the direction of the dotted lines h, thus forming the larger opening at f; and the smaller at e, coming against the guard D', which changes its course and is carried around in the manner before described. The case J may be made of any desirable proportion to enlarge or decrease the size of the jack. When the ship is tacking, the wind coming from different points, &c., this chimney jack is found to be of great practical utility, as it can be easily adjusted to currents of air from any direction.

What I claim as my improvement, and desire to secure by Letters Patent, is—

The slides B, adjustable hinged deflectors C, and guards D, in combination with the channel or chamber I, and case J, arranged in the manner and for the purpose set forth.

JNO. KINGSBOROUGH.
